CLAIM

The ornamental design for a digital photo frame, as shown and described.

DESCRIPTION

FIG. 1 is a front perspective view of my ornamental design for a digital photo frame;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the figures are for the purpose of illustrating portions of the digital photo frame, which form no part of the claimed design.

1 Claim, 7 Drawing Sheets
